PANEL FOR A FIRE ALARM STATION
OR SIMILAR ARTICLE

Willis G. Holmes, York St., York Harbor, Maine

Filed Jan. 5, 1961, Ser. No. 63,453

Term of patent 14 years

(Cl. D72—1)

FIG. 1 is a plan view of a panel for a fire alarm station or similar article showing my new design;

FIG. 2 is a side elevation looking from the right of FIG. 1;

FIG. 3 is a side elevation looking from the left of FIG. 1;

FIG. 4 is a top view; and

FIG. 5 is a bottom view.

The dominant features of my new design reside in the full line portions of the drawing.

I claim:

The ornamental design for a panel for a fire alarm station or similar article, substantially as shown and described.
